METHOD AND APPARATUS FOR TESTING AND TRUING EMERGENCY VALVES OF TRIPLE VALVES

Application filed May 1, 1928. Serial No. 274,273.

This invention relates to new and useful improvements in means for truing and testing malleable emergency valves of triple valves, employed in railway rolling stock air brake systems, and has for its primary object to provide means and a method whereby it can be determined whether a malleable steam valve is true with all its component parts, true and properly correlated, and to expediently effect such truing and correlation of parts, if it is found not to exist.

Another important object of the invention is to provide means and a method for dressing up the seating gaskets of such valves by employing a trued part of the latter as guide means for the dressing up operation.

Other objects and advantages of the invention will become apparent during the course of the following description:

In the drawings forming a part of the description, and wherein like numerals are employed to designate like parts through the several views:

Figure 1 is a side elevation of the truing device.

Figure 2 is a vertical longitudinal section of the same, illustrating an emergency valve being trued therein.

Figure 3 is a top plan of the lower die of the truing device.

Figure 4 is a bottom plan of the upper die of the truing device.

Figure 5 is a vertical longitudinal section of a testing and dressing up device, illustrating an emergency valve associated therewith.

Figure 6 is a top plan of said testing device.

Figure 7 is a vertical longitudinal section taken through the upper portion of a modified form of testing device, and

Figure 8 is a top plan of the same.

By way of introduction, and in order that the various functions of the apparatus may be more clearly understood and appreciated, it may be stated that the present invention is designed to restore and true up emergency valves of triple valves to bring them back to their standard and operative condition. Such emergency valves are employed in

triple valves of railway rolling stock air brake systems, and form a very vital part of such triple valves inasmuch as they control the emergency application of brakes on railway rolling stock, and therefore must be maintained in the prime of condition in order to prevent leakage of air pressure from the main reservoir to the brake side of the system, so as to prevent a premature application of the brakes or a condition causing the car wheels to drag and become flattened. The repair of flattened rolling stock wheels is an expensive proposition, and it has been definitely determined from actual experience that this expenditure can be saved in a large measure by maintenance of these emergency valves in standard and true condition so as to eliminate any possibility of a premature application of the brakes caused by an improper seating of the emergency valve.

These emergency valves are constructed of malleable metal, such as brass, and as shown in the drawings, comprise a valve body in the form of a disk 10 formed integral between the ends of a valve stem, the normal upper end 11 of which is elongated and slightly tapered as at 12 at its extremity for reception in the socket of a piston valve of a triple valve, and constitutes what may be termed an upper stem on the valve, while the other end 13 of the valve stem, which projects from the opposite side of the disk 10 coaxial with the stem 11, forms a lower stem, the end 14 of which is reduced to provide a shoulder 15 for the abutment of an emergency valve spring, which is slidably received in the socket of an auxiliary valve of the triple valve in a manner well understood. The valve disk 10 is provided with an annular flange projecting beyond the disk and concentric with the valve stem to form a seat for a ring-shaped rubber gasket 17, which is removably retained therein by means of a washer 18, and a nut 19 threaded upon the threaded portion of the stem 11, as clearly shown in Figure 5.

These emergency valves being constructed of malleable material, such as brass, frequently become damaged, due to handling

and transportation prior to their assembly in triple valves, and also after they are assembled and go into actual operation in triple valves installed in rolling stock, due to the impacts this valve receives from abutment with the piston valve whenever an emergency application of the brakes is made. This damage to the valve usually consists of the stems 11 becoming bent, sometimes 5 the valve body disk 10 becoming bent out of its true perpendicular relation to the valve stem, and frequently the rubber gaskets 17 become worn, or foreign matter in the air line lodges thereon, any one of such 10 conditions of the valve causing it to seat improperly, and thereby permit a leak from the main pressure side of the air brake system to the brake side, causing the premature application of the brakes to the wheels of 15 the rolling stock. Having determined the cause for the excessive number of flat wheels caused on railway rolling stock, equipped with air brake systems, the means and method for correcting the cause of this trouble 20 has been devised to restore such emergency valves to their normal or standard condition 25 in a most simple and effective manner.

After a defective emergency valve 10 has been removed from the triple valve or before 30 a new valve from stock is used in a replacement, the rubber gasket 17 is removed from the emergency valve by moving the nut and washer 19 and 18 so that the valve is in the condition shown in Figure 2 of the drawings. This valve is then placed in a cylindrical die member 20 equipped at one end with flattened wrench or vise faces 21, whereby the die member may be supported in a wrench, vise, upon 35 a bench or in any other suitable manner, so as to preferably retain it in the upright position shown in the drawings. This die member is formed of any kind of hard metal such as case hardened steel, and is equipped 40 with a central longitudinal bore 22 which is accurately machined to receive only true and unbent valve stems. The upper portion of this bore is enlarged as at 23 to receive the threaded and enlarged portion 45 of the valve stem, as shown in Figure 2, with the under face of the valve body disk 10 resting upon a truing surface perpendicular with the bore 22, and assuming the form, in 50 the present instance, of an annular anvil 55 24 concentric with the bore 22. Spaced from and concentric with this annular anvil 24 is an annular skirt or sleeve 25 integral with the die 20 so as to provide an annular depression or groove 26 surrounding the anvil 24 or truing surface 24 thereby forming a 60 pocket for the reception of the annular flange of the valve disk 10. The upper or truing surface of the anvil 24 is spaced such distance above the bottom of the groove 26 as 65 to prevent contact of the lower edge of the

depending flange of the valve disk therewith during the truing operation.

The skirt or sleeve portion 25 of the die is of the same diameter as the main body of the die, but has its interior wall slightly flared upwardly to receive and guide a tapered extension 27 of a second or upper die member 28 having substantially the same diameter as the complementary die member 20. This tapered extension 27 is of a length 75 and taper enabling the extremity of the extension, which we term a hammer portion, to engage the body disk 10 of the valve, and press it down upon the anvil 24 to its proper position and corelation with the valve stem 80 without binding in the skirt portion, and without a shoulder 29 formed at the juncture of said extension 27 and the body 28 coming in contact with the upper edge of the skirt of sleeve portion 25 of the complementary die. This clearance is allowed so that the upper die may properly force the valve stem 11 down into the bore 22, to straighten the same in case it is bent, and the valve disk 10 down upon the anvil to 85 insure proper corelation between this disk and the valve stem without any binding taking place between the two die members to prevent their proper cooperation.

The outer end surface of the extension 95 27 of the die member 28 is machined perfectly at right angles to its longitudinal dimension, and a bore 30 extends axially throughout the length of this die member, and is machined to accurately fit true standard valve stems 13. This bore 30 is enlarged at its lower end, as at 31, and is carefully machined to accurately fit a true and standard stem portion 13 of the valve, while the smaller portion 30 of the bore is machined to accurately fit, true and receive the reduced extensions 14 of such valve stems.

The upper end of the bore 30 is enlarged as at 32 to removably receive a reduced extension 33 of an anvil knob or striking member 34, and not only serves to center an impact upon the upper die member 28; but its being removable, serves also to release any vacuum created in the bore 30 to facilitate separation of the die members and removal of the valve therefrom. Of course, this upper die member 28, as well as the anvil member 34, are formed of any suitable hard material, such as case hardened steel, which will withstand the impacts for truing the valves.

After the rubber gasket 17 has been removed from the valve, as stated before, the lower valve stem 11 is introduced through the truing surface or anvil 24 and led into the bore 22. If the stem 11 is perfectly true and unbent, it may be pushed all the way down into the bore until the valve body or disk 10 engages the truing surface or anvil 24. In the event of the valve stem 11 being bent and out of true with respect to the body 125

of the valve, it will be introduced down into the bore 22 as far as it will fall by gravity. In case either the valve stem is bent, or the valve disk 10 is not in proper right angular relation thereto, or one side of it is deflected from its true standard plane, the valve will not seat properly in the die member 20, and this will be, of course, an indication of a faulty valve.

The upper die member 28 is then positioned, so that its enlarged bore 31 will receive the enlarged portion 13 of the upper valve stem and is lowered upon the same so that the extension 27 is guided down into the socket of the skirt or sleeve 25 until the truing surface of the hammer extension 27 engages the upper surface of the valve disk 10, and the reduced extension 14 of the valve stem enters the bore 30. The removable striking cap or anvil 34 is then placed with its reduced extension 33 in the enlarged upper end 32 of the bore 30, after which the die member 28 is forced down into the lower die member 20 under pressure, and, preferably, under the impact of a blow, which forcibly moves the upper die member against the valve disk 10 and drives it down upon the anvil 24, and the stem 11 down into the straightening bore 22. After the malleable valve has been driven down so that its valve disk 10 rests upon the anvil 24, it is known that both of the stems 11 and 13 of the valve are straightened, and that the valve disk 10 has again been restored to its proper correlation with the two valve stems, so that the disk stands exactly perpendicular to both of these stems, due to the fact that the two die members are exactly centered, and the surfaces of which are carefully machined to accurately fit the contacting parts of a standard true valve.

After this truing operation has been performed, there is a possibility that the rubber gasket 17 does not possess a true seating surface, or that it may become bulged when it is reseated in the flange 16 of the valve and the nut 19 and washer 18 have been placed upon the valve stem 11, so that we have provided means for giving the valve a final test as to its accuracy, as well as to dress the rubber gasket up so that its seating surface is absolutely perpendicular to the stem 11. This testing device is in the form of what may be termed a gauge 35 consisting of a cylindrical piece of relatively hard and tough material, such as case hardened steel. This gauge is equipped with a central axially extending bore 36 which is accurately machined to admit only absolutely true valve stems, and its lower portion is threaded, as at 37, whereby it may be mounted upon a rotating instrumentality, such as a shaft, for a purpose which will presently appear. A laterally extending orifice 38 extends from the exterior surface

of the gauge into the bore 36 to provide a vacuum release to facilitate removal of the valve.

The end of the bore 36 opposite the threads 37 is enlarged, as at 39, to freely receive the nut and washer of the valve that is placed in the gauge so that the seating surface of the rubber gasket may freely rest upon the truing surface 40, which is carefully machined so as to be disposed at exactly right angles to the axis of the bore 36. In the modification shown in Figures 5 and 6, a disk of emery cloth 41 is adhesively secured to the truing surface 40 and is equipped with a central opening 42 of the same size as the enlarged circular portion 39 of the bore, so as to admit the washer 18 and to permit the seating surface of the washer 17 to engage the emery cloth. The gauge 35 is preferably rotated by any suitable means, while the upper stem 13 of the valve is held stationary by the fingers so that the emery cloth 41 will abrade the seating surface of the gasket. Upon removal of the valve from this gauge, its gasket may be inspected to determine whether there are any high points which have not been sufficiently dressed off, or in case of flagrant irregularities, may be determined by leaving the valve in the gauge and determining whether there is any space between the seating surface of the gasket 17, and the abrasive element 41. In case it is found necessary to further dress off any high points on the gasket, the gauge is rotated until the seating surface of the gasket is given a surface which is uniformly at right angles to the valve stem, at which time it is known that the valve and its gasket have been restored to their true and standard condition, so that the valve may be then assembled in a triple valve without any danger of its failure to function as it should.

In Figures 7 and 8, a modified form of abrasive surface is provided for the gauge 35, which consists of seating a ring of carborundum, or any other suitable abrasive material 42, in an annular recess 43 of the truing surface 40, concentric with the bore 36 and its enlarged portion. The testing and dressing up of the gasket is carried out in the same manner as with Figure 5.

Although we have illustrated specific examples of our truing and testing device, for a particular kind of emergency valve used in conjunction with triple valves, it is to be understood that our invention is not limited to this particular type of valves, as many other types can be trued and tested with the same method and apparatus, or with slight modifications thereto.

It will also be understood that various changes in the size, arrangement and shape of the various parts may be resorted to with

out departing from the spirit of the invention, or the scope of the appended claims.

We claim:

1. The method of testing and truing double stem valves comprising a pair of stems extending from opposite sides of a valve disk, consisting in passing one of the stems through a truing surface and into a truing bore of a size to receive only true stems, inserting the other valve stem through the second truing surface and into a truing bore of a size to receive only true stems and then moving one truing surface toward the other to engage said valve disk to straighten both of said stems.
2. The method of testing and truing double stem valves comprising a pair of stems extending from opposite sides of a valve disk, consisting in passing one of the stems through a truing surface and into a truing bore of a size to receive only true stems, inserting the other valve stem through the second truing surface and into a truing bore of a size to receive only true stems and then moving one truing surface toward the other to engage said valve disk to straighten both of said stems, and to exert pressure upon said valve disk to restore correct relationship between said disk and both of said stems.
3. The method of testing and repairing emergency triple valves having rubber gasket seats, consisting in first removing said gasket from the valve body, forcing said valve stem through a truing surface and into a truing bore of a size to receive only true stems, replacing said gasket and then rotating said valve in a truing abrasive instrumentality to determine the relation of the gasket with respect to said corrected valve.
4. The method of truing and testing emergency triple valves having rubber gasket seats, consisting in first removing said gasket from the valve body, passing the valve stem through a truing surface and into a truing bore of a size to snugly receive only true stems, exerting a pressure upon said valve body in a direction parallel to said truing opening, replacing said gasket, and then rotating said valve in a truing abrasive instrumentality to determine the relation of the gasket with respect to said corrected valve.
5. A testing and truing device for double stem disk valves comprising a pair of relatively movable dies, each having a truing surface for engagement with opposite sides of the valve disk, each die being provided with a truing bore for the reception of one stem of the double stem valve, said dies being adapted to be pressed together to cause said truing surfaces to move together to straighten said stems and to dispose said disk in proper relationship to said stems.
6. A testing and truing device for double stem disk valves comprising a pair of relatively movable dies, each having a truing surface for engagement with opposite sides of the valve disk, each die being provided with a truing bore for the reception of one stem of the double stem valve, said dies being adapted to be pressed together to cause said truing surfaces to move together to straighten said stems and to dispose said disk in proper relationship to said stems.
7. A testing and truing device for double stem disk valves comprising a pair of relatively movable dies, each having a truing surface for engagement with opposite sides of the valve disk, each die being provided with a truing bore for the reception of one stem of the double stem valve, said dies being adapted to be pressed together to cause said truing surfaces to move together to straighten said stems and to dispose said disk in proper relationship to said stems, and means for guiding and maintaining said dies in axial alignment with each other during relative movement.
8. A testing and truing device for double stem disk valves comprising a pair of relatively movable dies, each having a truing surface for engagement with opposite sides of the valve disk, each die being provided with a truing bore for the reception of one stem of the double stem valve, said dies being adapted to be pressed together to cause said truing surfaces to move together to straighten said stems and to dispose said disk in proper relationship thereto, one of said dies having an elongated guide socket concentric with said bore, and the other having an elongated guide extension concentric with its bore to slide within said socket to guide and maintain said dies in axial alignment with each other during their relative movement.
9. A truing device for double stem valves comprising a pair of relatively movable dies, one of said dies having an annular raised anvil and a truing bore concentric therewith to receive one of said valve stems, said bore adjacent said anvil being enlarged, a second die having a circular hammer surface and a truing bore concentric therewith to receive the other valve stem, said dies adapted to be arranged with their bores aligned and to move together to cause said hammer surface to drive the disk of said valve upon said anvil.
10. A truing device for double stem valves comprising a pair of relatively movable dies, one of said dies having an annular raised anvil and a truing bore concentric therewith to receive one of said valve stems, said bore adjacent said anvil being enlarged, a second die having a circular hammer surface and a truing bore concentric therewith to receive the other valve stem, said dies adapted to be arranged with their bores aligned and to move together to cause said hammer surface to drive the disk of said valve upon said anvil, and a striking anvil removably associated with said bore of said second die.
11. A truing device for double stem valves comprising a pair of relatively movable dies, one of said dies having an annular raised anvil and a truing bore concentric therewith to receive one of said valve stems, said bore adjacent said anvil being enlarged, a guide skirt extended from said die con-

centric with said anvil, a second die having a circular hammer surface and a truing bore concentric therewith to receive the other valve stem, said second die having an elongated guide extension for a sliding fit with said skirt to maintain alignment of said bores, and cause said hammer surface to move parallel to said anvil, said dies adapted to be arranged with their bores aligned and move together to cause said hammer surface to drive the disk of said valve upon said anvil.

11. A truing device for stem valves comprising an anvil upon which the body of the valve is positioned, and a die having a truing surface and a bore to receive the valve stem and adapted to be moved upon said valve stem toward said anvil to cause its truing surface to force said valve body to fit perfectly upon said anvil.

12. A truing device for stem valves comprising an anvil upon which the body of the valve is positioned, a die having a truing surface and a machined bore to receive only true valve stems, and an anvil removably associated with said bore and adapted to center a blow upon said die to force it upon said valve stem toward said first named anvil to cause its truing surface to force said valve body to fit perfectly upon said anvil.

13. The method of truing stem valves consisting in passing the valve stem through a truing body and into a truing bore of a size to receive only true stems, and then exerting pressure upon said valve body with means guided by said truing body.

14. The method of truing distorted stem valves consisting of passing the valve stem through a truing surface and into a truing bore of a size to receive only true stems, exerting pressure upon the body of the valve in a guided direction co-axial with said truing bore, and forcing the valve body toward said truing surface by said co-axial pressure while the stem is being forced into said bore until the valve body is forced against said truing surface to correct any inaccuracy of relation between the stem and body of the valve.

15. The method of truing distorted stem valves consisting of passing the valve stem through a truing surface and into a truing bore of a size to receive only true stems, and then moving a member in a guided path co-axial with the truing bore to subject the body of the valve to pressure directed axially of said bore to force a bent stem into said bore to straighten the same while forcing the valve body toward and against said truing surface until the valve body is disposed substantially co-planar to the truing surface to correct any inaccuracy of relation between the stem and body of the valve.

16. A truing device for distorted disc stem

valves comprising a die having a truing surface and a truing bore of a size to receive only true stems, and a hammer blow receiving member entirely disconnected from the die and having a truing surface adapted to engage the disc of the valve, said member having guide means cooperating with the die upon impact delivered to the member to force the disc against the truing surface and the bent stem into the bore.

17. A truing device for distorted stem disc valves comprising a die having a truing surface and a truing bore of a size to receive only true stems, a hammer blow receiving member entirely disconnected from the die and having a truing surface adapted to engage the disc of the valve, said member having a blow receiving surface to receive impacts to force the disc against the truing surface and the bent stem into the truing bore.

18. A truing device for distorted stem disc valves comprising a die having a truing surface and a truing bore of a size to receive only true stems, a hammer blow receiving member entirely disconnected from the die and having a truing surface adapted to engage the disc of the valve, and an anvil carried by said member co-axial with the truing bore to receive a blow to force the disc against the truing surface and the bent stem into the truing bore.

19. A truing device for distorted stem valves comprising a pair of relatively movable dies, one of said dies having an annular raised anvil and a truing bore concentric therewith to receive the valve stem, the other die having a truing surface concentric therewith, and said dies adapted to be arranged with their axes aligned and to move toward each other to cause said truing surface to drive the disc of said valve upon the anvil and the stem into said truing bore.

20. A truing device for distorted stem disc valves comprising a pair of relatively movable dies, one of said dies having an annular raised anvil and a truing bore concentric therewith to receive the valve stem, the other die having a truing surface, said dies adapted to be arranged with their axes aligned and to move toward each other to cause said truing surface to drive the disc of said valve upon said anvil, and a striking anvil carried co-axially by said second named die.

21. A truing device for distorted disc stem valves comprising a pair of relatively movable dies, one of said dies having an annular raised anvil and a truing bore concentric therewith to receive the valve stem, a guide skirt extended from said die concentric with said anvil, the other die having a circular truing surface and an elongated guide extension adapted to slidably fit within said guide skirt to maintain alignment of said dies and to cause said truing

surface to move parallel to said anvil, said dies adapted to be arranged with their axes aligned and to move toward each other to cause said truing surface to drive the disc of the valve upon said anvil and the stem into said truing bore.

22. A truing device for distorted stem disc valves comprising a pair of relatively movable dies, one of said dies having an annular raised anvil and a truing bore concentric therewith to receive the valve stem, said bore adjacent said anvil being enlarged, the other die having a truing surface adapted to abut the disc of the valve, and said dies adapted to be arranged with their axes aligned and adapted to be moved toward one another to cause said truing surface to drive the disc of said valve upon said anvil and the valve stem into said truing bore.

23. A truing device for distorted disc stem valves comprising a pair of relatively movable dies, one of said dies having a circular anvil and a truing bore concentric therewith to receive the valve stem, an upwardly tapering guide skirt extended from said die concentric with said anvil, the other die having a truing surface and an elongated tapered guide extension for sliding fit within said skirt to maintain alignment of said dies and to cause the truing surface to move parallel to said anvil, said dies adapted to be arranged with their axes aligned and to move toward each other to cause said truing surface to drive the disc of the valve down upon said anvil and the valve stem down into said truing bore.

In testimony whereof we have hereunto set our hands.
